CONTAINER WITH POURING SPOUT AND CLOSURE

Clifton H. Phillips, Demarest, N. J., assignor to Shell Development Company, Emeryville, Calif., a corporation of Delaware

Application September 4, 1953, Serial No. 378,615

10

8 Claims. (Cl. 222—520)

This invention relates to containers for liquids, such as oils or chemicals, and is more particularly concerned with the construction of the spout and closure therefor, and with the arrangement of such spout and closure in relation to the outline of the container so as to insure that the container has good warehousing and stacking characteristics.

Containers for liquids, such as the common two-gallon tinned sheet metal cans, are usually provided with a nozzle extending upwards from the top wall about a discharge opening, the nozzle being embossed to provide screw threads for engagement with a closure cap; in most instances also a rigid strap handle is fixed to the top wall. The closure cap and handle extend above the plane of the top of the marginal chime, so that it is difficult to package, stack and warehouse such cans, both from the point of view of waste of space and because the protruding nozzle and handle carry all of the stress between touching containers which results in deformation of the top wall of the container and often in leakage at the base of the nozzle where it is soldered to the top wall. Prior containers which avoided such protruding elements have been subject to certain drawbacks that have prevented their commercial use in quantity, including difficulties in effecting good pouring characteristics and dependable seals at the pouring spout, as well as complexity and high cost of construction.

It is an object of this invention to provide an improved container for liquids having a discharge opening in the top thereof and a pouring spout and closure associated with said opening that are substantially flush with the said top, whereby the container has improved stacking and warehousing characteristics. A specific object is to provide an improved sheet metal can having a top wall with a chime that extends only slightly above the inner portion of the wall—advantageously not more than about 0.1 to 0.3 inch—wherein the pouring and sealing appurtenances are all situated below the plane of the top of the chime.

Another object is to provide a container for liquids having in the top thereof a discharge opening and a movable pouring spout having a part thereof extending into said opening, e. g., one with a pouring lip and/or one which can be extended upwardly into pouring position, wherein simplified sealing means are provided including a peripheral seal flange on the spout overlying the outside of the said top for sealing engagement therewith and an inverted or plug type seal cap also extending into said opening and having a rim overlying the said seal flange for sealing engagement therewith and to force the said flange against the top of the container; the top of the container herein referred to may be the top wall of the container or some other part that is an element of the top. This sealing arrangement of the movable pouring spout is advantageously employed in a container of the improved stacking and warehousing characteristics according to the preceding paragraph but is not limited to use in such a container.

2

A further object is to provide an improved container of the character described and an improved pouring spout and closure combination that is simple and can be constructed and assembled at low cost.

Still further objects will become apparent from the following description.

In summary, the top of the container includes a wall having an opening and a nozzle extending from the said wall about the opening; a tubular pouring spout is movably secured within the nozzle with screw threads and has a peripheral, flexible seal flange above the said top; and a closure that is threadedly engaged by screw threads within the pouring spout has a rim pressing the seal flange against the said top, a fluid-tight seal being provided on both the upper and lower faces of the seal flange. The under side of the seal flange may bear on whatever part of the container top is situated immediately beneath it, e. g., the said top wall or a rim of the nozzle, depending upon the manner in which the nozzle is attached. According to a preferred embodiment constituting a special feature of the invention, the pouring spout is formed integrally with the seal flange and these parts are made of a high modulus elastomer whereby the said seal can be effected without the use of seal gaskets. According to another embodiment the pour spout has a pouring lip of sprung metal which can lie flat against the said top wall for storage or be snapped upward for pouring liquid.

The container of improved warehousing characteristics includes the arrangement described in the foregoing paragraph, the nozzle being mounted to extend downwardly into the container. By using a closure with a reasonably thin rim, the seal flange and closure can both be made to lie below the top plane of the marginal chime of the top although the latter extends only slightly above the top wall of the container.

The invention will be further described with reference to the accompanying drawings forming a part of this specification and showing certain preferred embodiments thereof by way of illustration, wherein:

Figure 1 is an exploded elevation view, partly in section, of a container with the closure removed and the spout in pouring position;

Figure 2 is a plan view of the container with the closure in place;

Figure 3 is a vertical sectional view, on an enlarged scale, of a portion of the container with the closure in place;

Figure 4 is a fragmentary view similar to Figure 3 showing a modified arrangement of the nozzle;

Figure 5 is an exploded elevation view, partly in section, of a different embodiment of a container with the pouring spout and closure removed;

Figure 6 is a plan view of the container according to Figure 5 with the pouring spout and closure in place;

Figure 7 is a vertical sectional view, on an enlarged scale, of a portion of the container of Figure 5 with the pouring spout in storage position and the closure in place;

Figure 8 is an elevation view of a modified pouring spout, and

Figure 9 is a plan view of the spout shown in Figure 8.

Referring to the drawings in detail, and particularly to Figures 1-3, all parts, except for the closure plug and as otherwise indicated, are made of thin sheet metal, e. g., 0.008 to 0.015 inch thick, preferably tinned, and the thickness is necessarily exaggerated in the drawings. The container has upright side walls 10 connected to bottom and top walls 11 and 12, respectively, by hermetic seams of any suitable form, such as the double seams shown to provide chimes 14 and 15, respectively.

For good storage characteristics the walls 11 and 12 are substantially rectangular, except for rounding of the corners, but this feature is not essential and the invention may be applied to containers of other outlines. The carrying handle, when provided, is preferably of the hinged type, as shown at 16, secured by staples 17 soldered to the wall 12 so as to lie almost flush therewith, entirely beneath the plane of the top of the chime 15.

The top wall 12 has a discharge opening near one margin thereof about which there is a nozzle 19; the nozzle is affixed to a part of the container top. The nozzle is made of thin sheet metal and is embossed to provide screw threads and a mounting flange 20 therein, by which the nozzle is fixed to the top wall by soldering, although tightness is not essential to the sealing action of the closure to be described. It should be noted that the invention is not concerned with the specific manner in which the nozzle is secured to the top wall 12 or the fact that it is of thin embossed sheet metal but only with the fact that it is mounted to extend downwardly into the container and that it has internal screw threads; thus, the flange 20 may be on the upper side of the top wall and soldered to it as shown in Figure 4. In the case of Figure 4, the wall 12 may be bent inwardly to provide a bead 21 which serves to position the nozzle during the assembly thereof, and a hermetic seal between the nozzle and top wall is necessary. To facilitate discharge of liquid the nozzle is preferably provided with one or more lateral drain holes 22 situated just beneath the wall 12. Further, a venting tube 23 may be optionally provided and secured by soldering against the under side of the wall 12; as is well-known in the art, such a tube has an opening at one end 24 within the container displaced horizontally from the discharge opening and the other end 25 is bent up and in registry with holes 26 extending through the top wall and flange 20 spaced radially inwardly from the outer edge of the latter for communication with the atmosphere when the closure is removed.

The pouring spout comprises a tubular part 27 with external and internal screw threads, the former being of size and pitch to cooperate with the threads in the nozzle 19, a peripheral seal flange 28, and preferably a retaining lip 29 at the bottom. The flange 28 may have a pair of tabs 28a protruding radially outwards from and of the same thickness as the flange itself to facilitate getting hold of the spout for turning it. However, other expedients, e. g. serrating the edge of the flange 28, or giving it a non-circular shape, may be resorted to. In the preferred embodiment these parts are made integral and formed of a high modulus elastomer, preferably a synthetic elastomer, such as a plastic having sufficient rigidity to afford shape to the threaded tubular part and permit the spout to be screwed in and out, while yet being sufficiently pliant to permit the seal flange 28 to be flexed against the wall 12 and to effect a dependable seal by its own action, i. e., without the use of any additional deformable gasket or equivalent member. Examples of such elastomers are polyethylene, polyvinyl chloride, the copolymer of vinyl chloride with vinyl acetate, polyvinylidene chloride, the copolymer of polyvinylidene chloride with vinyl chloride and vulcanized rubber. The seal flange 28 overlies the portion of the container top immediately surrounding the discharge opening, viz., an annular portion of the wall 12 in Figures 1-3 and the mounting flange 20 in Figure 4, and is of sufficient width to cover the hole 26, when provided. Such elastomers can be deformed elastically without damage, and it is a special feature of this embodiment of the invention that the pouring spout can be formed in one piece with the retaining lip 29 prior to assembly to the container and can thereafter be attached by deforming the spout sufficiently to permit the lip to enter through the nozzle 19. One or more circumferentially elongate drain holes 30 are formed in the spout above the lip 29.

The closure cap is of the inverted or plug type and comprises an externally screw threaded shank 31 shaped to cooperate with the internal threads of the pouring spout and a rim 32 that is sufficiently rigid to force the seal flange 28 of the pouring spout firmly down against the container top to deform the flange slightly and to effect thereby a dependable seal both on the lower and upper faces of the seal flange. The cap advantageously has a central depression 33 with a bar 34, sometimes known as a bumped-in bar, to facilitate the use of a closing tool.

It is evident that when the spout is screwed fully down and the closure cap is tightened, as shown in Figures 3 and 4, the container is sealed. In this condition the handle and the closure cap are almost flush with the top wall, permitting all appurtenances to lie beneath the top plane of the chime 15 even when the latter extends only a minimal distance above the top plane of the wall 12, e. g., 0.1 to 0.3 inch. In Figure 3 the seal acts directly against the wall 12 and the flange 20 serves only to transmit mechanical stress.

To pour liquid from the container the cap is unscrewed and the pouring spout is raised by unscrewing it to any desired extent. When the container is nearly empty it is necessary to screw the pouring spout to a sufficient height to bring one or more of the holes 30 thereof into registry with a drain hole 22 to permit liquid from the container to enter the pouring spout despite depletion of the liquid to a level beneath the end of nozzle 19 when the can is in inverted position.

Figure 4 shows two modifications, of which the first, already noted, is the modified attachment of the nozzle. The other, which can also be applied to the other embodiments, involves the use of a flowed-in deformable annular gasket 35 of a synthetic elastomer that is permanently fixed to the under side of the flange 32 of the closure. Such a gasket would be used when the flange 28 is made of metal or other material that is not sufficiently deformable to form an effective seal alone. A similar flowed-in gasket 35a can also be applied to the under side of the flange 28.

Referring to Figures 5-7, the container, top and nozzle are formed as described above for Figures 1-3. The pouring spout 36, which is preferably made of sheet metal but may, if desired, be made of plastic material, also comprises a tubular part formed to provide external and internal threads. It has a drain hole 37 for registry with the hole 22; however, the hole 37 may be omitted since this part may be made short enough or removed to expose the drain holes 22 and permit the end contents of the container to drain out, although with loss of good pouring characteristics. The spout carries a pouring lip 38 which may be made integral with the tubular part, although other means of providing the lip may be used. The lip is embossed to a dished shape shown to produce a sprung metal shape in which the lip is stable in either of two positions, viz., with the point thereof downward bearing against the wall 12 as shown in Figure 7, or raised away from the wall as shown in Figure 5. The pouring spout carries a peripheral seal flange 39 which may be integral with the lip as shown and is sufficiently flexible to be urged into sealing engagement with the wall 12 by the closure cap.

The closure cap is of the type previously described, and includes a screw threaded shank 40, a rim 41, a depression 42 and a bar 43. In addition, a suitable sealing gasket 44 of a synthetic elastomer may be provided at the under side of the rim 41 when the seal flange is made of hard material such as metal. When the seal flange 39 is made of an elastomer the gasketing material may be omitted.

When the parts are disposed as shown in Figure 7 the pouring spout with its lip are almost flush to the wall 12 and lie below the plane of the top of the chime 15 and the container is in condition for packaging, storage and

shipment. The gasketing ring 44 provides an effective seal on the upper face of the seal flange 39 while the lower face thereof is sealed by metal-to-metal contact. A thin gasket may, of course, be interposed here if desired. To dispense liquid the closure cap is unscrewed, the end of the lip 38 being held to prevent rotation of the spout. The spout is then snapped up and turned to project over the margin of the top.

The several features shown in Figures 5-7 may be applied individually to the embodiments of Figures 1-4 and vice versa; for example, the spout 36 of Figure 5 may have a retaining lip or flange at the bottom, as shown at 29 in Figure 1.

To simplify assembly it is desirable that the spout be symmetrical about a horizontal plane, so that it would make no difference which end of the spout is inserted into the nozzle. Such a construction is shown in Figures 8 and 9, wherein the spout 47, made of an elastically deformable elastomer, has identical, integral seal flanges 48 and 48a at the ends thereof. The flange that is first inserted into the nozzle functions as a retaining lip while the other one performs the function described above for the flange 28. A plurality of drain holes 49, 49a and 49b are provided, the latter being situated at equal distances from their respective ends.

A further variant shown in these views is in the shape of the flange, which is here made hexagonal, permitting it to be engaged for rotation.

Any of the drain holes 49, 49a and 49b may be brought into registry with the drain hole 22 by turning the spout within the nozzle 19. To facilitate such registry it is advantageous to locate a hole at such a distance from each flange 48 and 48a that it is in registry with the hole 22 when the flange in question engages the bottom of the nozzle 19. Thus, the center hole 49 may in some cases satisfy both of these requirements and the other two holes may in such case be omitted; or, particularly in the case of longer spouts, the center hole 49 may be omitted.

I claim as my invention:

1. A container for liquid comprising a top having a discharge opening therein; a nozzle fixed to said top about said opening and forming a part thereof, said nozzle having internal screw threads; a pouring spout having a tubular part with external and internal screw threads situated within and in threaded engagement with said nozzle and having a peripheral flexible seal flange extending laterally outwards from the tubular part in sealed relation thereto and situated above said top for sealing engagement therewith; and an inverted type closure having a shank with external screw threads situated within and in threaded engagement with the said tubular part of the spout and having a peripheral rim extending laterally beyond the shank and over said seal flange for sealing engagement therewith and for urging said seal flange down against the top.

2. A container according to claim 1 wherein said seal flange is made of elastomer for effecting of itself a seal both on the upper and lower faces of the flange.

3. A container according to claim 1 wherein said pouring spout is made of a high modulus synthetic elastomer and has said seal flange integral therewith and made of like material.

5 4. A container according to claim 3 wherein said pouring spout has a lip integral with said tubular part thereof extending laterally outwards under the bottom of said nozzle for engagement with the bottom of the nozzle to limit the upward movement of the spout.

15 5. A container according to claim 1 wherein said pouring spout is symmetrical about a horizontal plane, whereby it has a peripheral flange at each end, said flanges being integral with the said tubular part and said pouring spout being made of elastically deformable material, whereby one of said flanges can be inserted through the nozzle by temporary deformation thereof, said one flange extending laterally outwards under the bottom of the said nozzle for engagement with the bottom thereof to limit the upward movement of the spout.

20 6. A container for liquid comprising a substantially flat top having a discharge opening therein; a nozzle fixed to said top about said opening and forming a part thereof, said nozzle having internal screw threads and extending downwardly from the top into the container; a pouring

25 spout having a tubular part with external and internal screw threads situated within and in threaded engagement with said nozzle and having a peripheral flexible seal flange at the upper extremity thereof extending laterally outwards and in sealed relation to said tubular part, said

30 seal flange being in sealing engagement with said top in substantially flush relation thereto; and an inverted type closure having a shank with an external screw thread situated within and in threaded engagement with the said tubular part of the spout and having a peripheral rim extending laterally beyond the shank and over said seal flange for sealing engagement therewith and for urging said seal flange down against the top.

35 7. A container according to claim 6 wherein said pouring spout is integral with said seal flange and both are made of a high modulus elastomer, the face on the rim of said closure and the part of the top in engagement with the under side of the seal flange being of metal, whereby the seal flange of itself effects a seal both on the upper and lower faces thereof.

40 8. A container according to claim 6 wherein said pouring spout has a sprung metal pouring lip extending beyond the said seal flange, said pouring lip being adapted to lie in substantially flush relation to said top and wholly within the outline of said top when the container is closed and being adapted to be snapped up to incline upwardly from said top when the spout is in pouring condition.
